UNITED STATES PATENT OFFICE.

CARL WERNER STUART, OF NEW YORK, N. Y.

GLOVE-FASTENING.

SPECIFICATION forming part of Letters Patent No. 362,553, dated May 10, 1887.

Application filed August 3, 1886. Serial No. 209,870. (No model.)

To all whom it may concern:

Be it known that I, CARL WERNER STUART, a subject of the King of Sweden and Norway, and a resident of New York, in the county of 5 New York and State of New York, have invented certain new and useful improvements in Fastenings for Gloves, Shoes, &c.; and I do hereby declare that the following is a full, clear, and exact description of the invention, 10 which will enable others skilled in the art to which it appertains to make and use the same, reference being had to the accompanying drawings, which form a part of this specification, and in which—

15 Figure 1 is a perspective view showing my improved fastening applied to the flaps of a glove, showing the same open. Fig. 2 is a perspective view showing the fastening applied to the flaps of the glove, and showing 20 the same fastened. Fig. 3 is a vertical sectional view taken longitudinally through the fastening as shown in Fig. 2. Fig. 4 is a transverse sectional view taken on the line *x x* in Fig. 3. Fig. 5 is a perspective view of the 25 movable link or fastener detached; and Fig. 6 is a perspective view showing the link or fastener applied to an ordinary button.

The same letters refer to the same parts in 30 all the figures.

This invention has relation to an improved fastening device for gloves, shoes, and other garments, which said device is also capable of being applied to buttons for the purpose of attaching the same to garments; and it has for 35 its object to provide a device of this class which shall possess superior advantages in point of simplicity, durability, facility of adjustment, and general efficiency.

With these ends in view the invention consists in the improved construction and operation of said fastening-device, which will be hereinafter fully described, and particularly pointed out in the claim. The chief part, however, of said device consists of an endless 45 link, whose function is similar to that of a curved knobbed bar already in use and whose construction, as well as function, resemble an endless link heretofore employed in a like combination, but the advantage which my link 50 possesses does not obtain in either of these devices, said advantage arising from the particu-

lar construction of said link, as will now be set forth.

In the drawings hereto annexed, A designates an eye or staple which may be attached to the flap B of a shoe, glove, or other garment in any suitable manner—for instance, as shown in the drawings hereto annexed—by making the said eye or staple part of or attached to a plate or washer, C, having struck-up prongs 60 D, which may be bent at right angles to the said plate or washer, so as to penetrate the garment-flap and pass through slots in a washer-plate, E, upon the under side of the garment-flap, after which the said prongs may be clinched, 65 thereby making a secure attachment. I would have it understood, however, that any other suitable method of attaching the eye A to the garment-flap may be resorted to without departing from the spirit of my invention. 70

F is the endless link mounted in the eye or staple A. This link, constructed of a flat strip of sheet metal, is compressed at the points G G, about equidistantly from each other and from the ends of the link, which latter is thereby subdivided into a central loop, H, and end loops, I I. The sides or edges of the central loop are provided with shallow notches or indentations J J, adapted to engage the eye or staple A, so as to prevent longitudinal displacement of the 80 link, whether its central loop is adjusted in the said eye or staple in a manner to cause the link to rest on its side or on edge. The other flap, K, of the glove, shoe, or other garment is provided with an eyelet, L, of such dimensions as 85 to admit of the link F passing readily through the same.

The operation of this invention will be readily understood from the foregoing description, taken in connection with the drawings hereto annexed, without requiring extended explanation. When it shall be desired to fasten the glove or other garment to which the device is applied, the link F is drawn through the eye or staple A until the latter rests in one of the 90 end loops of said link, the compressed portions G G acting, by reason of the elasticity of the metal of which the link is constructed, as spring snaps or latches to prevent displacement of the link from the position to which it 95 may have been adjusted. The opposite end of the link is then passed from the under side 100

through the eyelet of the opposite garment-flap, after which, by using the link as a lever, the flaps may be readily drawn together and the link passed entirely through the eyelet 5 until the latter passes over the eye or staple A. The link may then be drawn back through the staple until the latter rests in the notches of the central loop, H, of the said link, as shown in Figs. 2 and 4 of the drawings, when the 10 fastening is complete. The notches or indentations J serve, in conjunction with the compressed or spring portions G of the link, to prevent longitudinal displacement of the latter. 15 In Fig. 6 of the drawings I have shown my improved link or fastener applied to an ordinary button, N, the eye of which takes the place of the eye or staple A. The button thus equipped may be used as a cuff-button, or for 20 cuffs, vests, and other garments, which will be provided with a small slit or eyelet button-hole for the passage of the fastening-link and the buttons hank or eye. The device thus forms a

simple, convenient, efficient, and inexpensive attaching or fastening device for the buttons 25 equipped therewith.

Having thus described my invention, I claim and desire to secure by Letters Patent of the United States—

The combination, with an eye or staple, of a 30 movable and reversible endless link arranged in the same, said link being constructed with laterally-compressed portions, whereby a central loop, H, and end loops, I, are formed, the sides or edges of the said central loop being 35 provided with recesses or indentations J, thereby adapting it to engage the said eye or staple, whether said link rests on the side or on edge, substantially as shown and described.

In testimony that I claim the foregoing as 40 my own I have hereunto affixed my signature in presence of two witnesses.

CARL WERNER STUART.
